UNITED STATES PATENT OFFICE.

SYLVANUS HAROLD STOLTZFUS AND ARTHUR SAMUEL WOLF, OF
CHAMBERSBURG, PENNSYLVANIA.

DUST-COLLECTOR.

No. 833,490.

Specification of Letters Patent.

Patented Oct. 16, 1906.

Application filed December 12, 1905. Serial No. 291,459.

To all whom it may concern:

Be it known that we, SYLVANUS HAROLD STOLTZFUS and ARTHUR SAMUEL WOLF, citizens of the United States, residing at Chambersburg, in the county of Franklin and State of Pennsylvania, have invented a new and useful Dust-Collector, of which the following is a specification.

This invention relates to dust-collectors of the balloon type, in which a plurality of series of filtering-tubes are supported annularly in a rotary member, said member being intermittently rotated to place the series of filtering-bags in succession in registry with a conveyer-box, mechanism being provided for agitating the filtering-bags that are in registry with the conveyer-box to loosen the dust adhering thereto and to cause it to drop into the box.

Among the objects of the present invention are to combine the advantages of what is known as a "Cyclone" dust-collector with those of a dust-collector in which the air is caused to pass through tubular filtering-bags, whereby the dust is separated and the air is purified and to provide for the preliminary removal from the dust-laden air of the coarse particles held in suspension therein prior to the passage of the air to the filtering-bags in a simple and improved manner.

Further objects are to promote simplicity, durability, and general efficiency in the construction of the machine.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that changes, alterations, and modifications within the scope of the invention may be resorted to when desired.

In the drawings, Figure 1 is a side elevation, partly in section, of a dust-collector constructed in accordance with the principles of the invention. Fig. 2 is a vertical sectional view taken on the plane indicated by the line 2-2 in Fig. 1. Fig. 3 is a detail

view of an expandable packing-ring used in connection with this invention. Fig. 4 is a detail plan view of the mechanism for rotating the filtering-drums. Fig. 5 is a sectional detail view, on an enlarged scale, illustrating the connection with the filtering-drum of one of the filtering tubes or bags.

Corresponding parts in the several figures are indicated throughout by similar characters of reference.

The frame of the machine includes side members 1-1, intermediately between which are disposed the side members 2-2 of the casing C, which is of approximate inverted ovoid shape, said casing being intersected at its upper end by a flue 3, the upper wall of which is approximately tangential to the upper portion of the casing. This flue is provided with a closure 4, which is concentric with and constitutes a temporary portion of the wall of the casing, said closure being disposed adjacent to either side of the casing and supported in such a manner as to make it interchangeable from one side to the other of the casing. The flue 3 constitutes the inlet for dust-laden air, which is admitted at the end of the flue which is distant from the side of the casing at which the closure 4 is supported.

Interiorly upon the curved walls of the casing are disposed inclined troughs or baffles 5-5, serving to receive the comparatively-heavy dust particles which will flow by gravity over the baffles to the bottom of the casing and into a trough 6, containing a spiral conveyer 7, whereby the dust is discharged through an aperture 8 at one end of the trough.

The frame members 1-1 and the side members 2-2 of the casing C are provided with bearings for the rotary members or drums D-D, the inner ends of which are open and in communication with the interior of the casing C, while the outer ends of the drums have closures 9, which have been illustrated as supported by means of arched straps 10 from the frame members 1. The inner ends of the drums are provided with rings or hoops H, including the bands 11, flanges 12, and laterally-extending members 13, which latter engage the bearing-rings B in the sides 2 of the casing. At the outer ends of the drums are similar rings or hoops H', including the bands 11', flanges 12', and laterally-extending annular members 13', which latter engage

the bearings in the side members 1 of the frame. Upon the outer extremities of the bearing members 13' are formed ratchet-wheels 14.

5 The drums D D are provided near their inner and outer ends with radially-extending spokes 15, which are disposed in pairs around the circumference of the drum and which are connected by means of links or braces 16 in an annular series. The spokes 15 are provided at their outer extremities with reduced shouldered portions forming dowels 17 for the support of cross-bars 18 whereby the spokes are connected in pairs, said cross-bars being parallel to the axes of the drums. Springs 19 are coiled upon the dowel members for the purpose of forcing the cross-bars 18 normally in an outward direction.

20 The filtering tubes or bags 20 are constructed of textile or other suitable porous and flexible material in tubular shape, and are preferably made tapering, their outer ends being larger than their inner ends. The drums D are provided with perforations 21, having 25 seats 22 for the wire rings or fastening devices 23 at the inner ends of the tubes. The latter are provided at their outer ends with closures 24, secured, as by means of screws 25, to the cross-bars 18, which, being forced outwardly 30 by the action of the springs 19, will serve to hold the rows of filtering-tubes tight and taut.

35 The stationary heads 9 at the outer ends of the drums D are provided upon their inner sides with flanges or brackets 26, upon which are placed springs 27, serving to support a trough or casing 28, which is forced by the action of the spring 27 upwardly against the interior of the drums D, the trough 28 being of such width that one row of filtering-tubes 40 of each drum may communicate therewith when the drums are stationary. The trough 28 has a cover portion 29, which may be securely connected therewith and which extends transversely through the casing C, said 45 cover portion being of course of a size nearly sufficient to constitute a cover for that portion of the trough 28 which extends transversely through the casing C, which latter is not to an appreciable extent obstructed by 50 said trough and cover. Packing, as 30, and expandible packing-securing means, as rings 31, having inwardly-offset members 31^a surrounding the trough 28, are to be supplied at all needed points to make practically air-tight joints between the moving parts of the 55 machine and their bearings or contact-surfaces. Within the trough 28 is supported a spiral conveyer 32, operating to discharge the contents of the trough at one end into a tubular conveyer 33, whereby it is conducted to the conveyer-trough 6 near the discharge end of the latter.

60 The frame of the machine is provided near its upper end with bearings for the main shaft 34, carrying a band-wheel 35, which may be

driven from any suitable source of power. Bearings are also provided for a counter-shaft 36, carrying a spur-wheel 37, meshing with and driven by a pinion 38 upon the main shaft 34. The counter-shaft 36 has cranks 39, provided with wrist-pins 40, upon which are pivoted pawls 41, having hooked terminal ends 42, which are in gravity engagement with the ratchet-wheels 14. The number of teeth upon the latter is equal to the number of pairs of spokes radiating from the drums B, so that at each step or intermittent movement the drums will be rotated or advanced to an extent equal to the distance between the spokes. This movement may be easily 75 accomplished during less than one-half—say one-fourth—of the rotation of the shaft 36, owing to the fact that the throw or movement of the pawls is considerably in excess of the length of the ratchet-teeth, the drums being 80 at rest during the greater portion of the rotation of said shaft, and the position of the drums at rest being with one set or row of filtering-tubes in registry with the trough 28.

85 Supported slightly below the counter-shaft 36 is a shaft 43, upon which are pivoted frames, including side members 44, connected at their outer ends by cross-bars 45. The side member 44 of each frame is provided with a cam 46, lying in the path of the projection 47 upon the counter-shaft, and the outer frame-bars 45 are provided upon their under sides with cushions 48, of rubber or other suitable material, which are in alignment with and adapted to engage the cross-bars 18, connected with the tubular filtering-bags, which are in registry with the trough 28 when the drums are at rest. The cross member 45 of each frame is provided with a wear-plate 49, preferably of steel, which is in 100 alignment with and adapted to be engaged by a cam member 50 upon the main shaft 34.

105 The main shaft 34 carries a sprocket-wheel 51, which is disposed in the same vertical plane as sprocket-wheels 52 and 53 upon the shafts 54 and 55 of the conveyers 7 and 32, respectively. These several sprocket-wheels are connected by a link-belt 56, which also passes over a suitably-supported idler 57, whereby the conveyers 7 and 32 will be 110 driven in the proper direction directly from the main shaft.

115 In the trough 6 of the conveyer 7, near the outer end of the latter and inside of the point where the dust from the upper conveyer enters, is a hinged closure or valve V, which serves to prevent the draft of air through the conveyer-trough 6 from interfering with the gravity fall of dust from the upper conveyer.

120 In the lower part of the casing C, above the trough 6, is supported a vertically-disposed deflecting member 58.

125 At the end of the trough 28 which is distant from the outlet 33 of said trough is an aperture 59, from which extends a pipe 60, 130

the opposite end of which is in practice connected with the eye of the casing of a fan, the tendency of which is to exhaust air from the trough and which may be the fan that supplies the impure air to the dust-collector.

5 In operation the dust-laden air may be caused to enter into the casing C through either end of the flue 3, the closure 4 having previously been adjusted to deflect the air 10 downwardly into the casing within which it whirls about, the heavier dust particles being thrown by centrifugal force in the direction of the walls of the casing where they are intercepted by the baffles 5 5 and permitted to 15 settle by gravity into the trough 6, containing the screw conveyer 7, whereby it is expelled at one end of the trough. The deflector 58 will serve to intercept the whirling air-current, and the dust-laden air deprived 20 of the heavier and coarser particles will expand laterally within the drums and find an outlet through the porous filtering-bags upon the inner surfaces of which the fine dust particles will be deposited. In the meantime 25 the drums will be rotated intermittently by the pawl-and-ratchet mechanism described, the projections 47 upon the shaft 36 being so disposed that during the time when the drums are in motion the frames, including 30 the members 44 and 45, will be elevated so as to present no obstacle to the movement of the drums. As soon as the drums become stationary the projections 47 become disengaged from cams 46, and the frames will thus 35 be permitted to drop with the cushions 48, impinging upon the cross-bars 18, with which they are in alinement. The cams 50 upon the main shaft 34, which latter rotates much more rapidly than the counter-shaft, will 40 now engage the wear-plates 49 upon the cross-bars 45, depressing the latter and simultaneously depressing the cross-bars 18 against the tension of the supporting-springs 19. As soon as the cams 50 pass out of engagement with the cross-bars 48 the springs 45 19 will expand, forcing the cross-bars 18 suddenly in an outward direction, and thus stretching the material of which the tubular filtering-bags are composed with a sudden 50 snap, which is effective in dislodging the particles of dust upon the inner surfaces of said bags, causing the dust to drop into the trough 48, where it is disposed of by the spiral conveyer, which carries it to the conducting-pipe 33, whereby it is delivered into 55 the discharge end of the conveyer-trough 6.

As will be seen from the foregoing description, this improved machine is constructed with a view to combining within a single 60 structure all the advantages of that class of dust-collectors which are of the well-known "Cyclone" type and in which the separation of the dust from the air is effected by centrifugal action, owing to the natural tendency of the heavier particles held in sus-

pense in a whirling air-current within the casing to move from the center of said current in the direction of the walls of the casing and that class of dust-collectors in which the dust-laden air is strained and purified 70 through a filtering medium which in the present instance is composed of the tubular filtering-bags.

Having thus described the invention, what is claimed is—

75

1. In a dust-collector, an inverted ovate settling-chamber having dust-gathering baffles upon its inner walls, an axial aperture in one of its side walls, and an inlet for dust-laden air consisting of a flue with its upper 80 wall approximately tangential to the upper portion of the chamber, in combination with a filtering-drum supported for rotation adjacent to the side wall and communicating with the settling-chamber through the axial aperture in the side wall of said chamber.

2. In a dust-collector, an inverted ovate casing constituting a settling-chamber and having dust-gathering baffles upon its inner walls and an axial aperture in one side wall, a 90 flue intersecting the upper part of the chamber and having an upper wall approximately tangential thereto, and a closure in said flue constituting a part of the wall of the casing; in combination with a filtering-drum supported for rotation adjacent to the side wall 95 and communicating with the settling-chamber through the axial aperture.

3. In a dust-collector, an inverted ovate casing having dust-gathering baffles upon its 100 inner walls and an axial aperture in one side wall, a flue intersecting the upper part of the casing and having an upper wall disposed approximately tangential thereto, and a closure in said flue movable from one side of the 105 casing to the other side, in combination with a filtering-drum supported for rotation adjacent to the side wall and communicating with the settling-chamber through the axial aperture.

4. In a dust-collector, an inverted ovate settling-chamber having dust-gathering baffles upon its inner walls, an axial aperture in one of its side walls, and an inlet for dust-laden air consisting of a flue with its upper 115 wall approximately tangential to the upper portion of the chamber, a receiving trough at the lower end of the casing, a carrier in said trough, and a deflector disposed vertically above the trough; in combination with 120 a filtering-drum supported for rotation adjacent to the side wall and communicating with the settling-chamber through the axial aperture.

5. In a dust-collector, an intermediate settling-chamber having a tangential inlet for dust-laden air near its upper end and a dust-exit near its lower end the side walls of said casing being provided with axial apertures, in combination with hollow drums supported 125 130

for rotation adjacent to the opposite side walls and communicating with the settling-chamber through the axial apertures in the side walls, filtering-tubes extending radially from the drums, spring-supported means for keeping the tubes stretched and taut, and means for vibrating the tubes.

6. In a dust-collector, a settling-chamber having an inlet at its upper end for dust-laden air and an exit at its lower end for dust, said chamber being provided with axial apertures in its opposite side walls, hollow filtering-drums journaled at their inner ends in said apertures and communicating with the settling - chamber therethrough, bearing-rings having laterally-extending flanges supporting the outer ends of the drums, closures at the outer ends of the drums, and filtering means connected with and carried by the latter.

7. The combination with an intermediate settling-chamber, of drums supported for rotation adjacent to the sides of and in com-

munication at their inner ends with said settling - chamber, stationary closures at the outer ends of the drums, means for intermittently rotating the drums step by step, filtering-tubes extending radially from the drums, spring-supported members connected with and supporting the outer end of the filtering-tubes, a dust - receiving trough extending through the drums and the casing, a cover for that portion of the trough which extends through the casing, a conveyer in said trough, and means for agitating the spring-supported supporting members of the filtering-tubes which are temporarily in alinement with the receiving-trough.

In testimony that we claim the foregoing as our own we have hereto affixed our signatures in the presence of two witnesses.

SYLVANUS HAROLD STOLTZFUS.
ARTHUR SAMUEL WOLF.
